UNITED STATES PATENT OFFICE.

DAVID RONALD WALLACE, OF JOPLIN, MISSOURI.

TELEPHONE RECEIVER.

Application filed November 16, 1923. Serial No. 675,206.

This invention relates to improvements in telephone receivers and more particularly to that type especially adapted for use with radio apparatus.

5 One of the objects of the present invention is to provide a receiver of the above general character known as the watch case type of simple and practical construction and which will be exceedingly sensitive in 10 use and operation.

The receiver in question is provided with two pole pieces one of which is inside of the other, the inside pole piece passing through a coil and transmitting near the center of 15 a diaphragm while the outside pole piece is provided with knife edges which support the diaphragm near its outer edge.

In the accompanying drawings wherein is shown two of various possible modifications, 20 Figure 1, is a vertical sectional view showing such parts as are necessary to fully understand the invention.

Figure 2 is a partial sectional side elevation of the device shown in Figure 1.

25 Figure 3 is a vertical sectional view showing a slight modification.

Referring particularly to Figure 1 numeral 12 indicates a cup shaped casing made of insulating material upon which is threaded the cap ear-piece 13 also made of insulating material. Within the casing and conforming approximately to the inner dimensions of the casing is a cup shaped magnetic pole piece 6 that is fastened to the casing by 30 means of screws 30 secured through the base of the casing and threaded into the magnetic pole piece 6. The rim of the magnetic pole piece 6 is bevelled to form a knife edge as shown at 7 and upon which rests the diaphragm 8, that is preferably made thinner around its periphery than near its center to 35 increase its flexibility.

Through the central portion of the base of the magnetic pole piece 6 is threaded a permanent magnet 3 that extends from a short distance on the outside of the casing 12 to a point in close proximity to the diaphragm 8 when flexed inwardly by the pull exerted thereon by the pole of magnet 3. Upon the 45 outer end of magnet 3 there is member 22 rigidly affixed thereto for adjusting the inner tip of the magnet 3 toward or away from the diaphragm 8. Threaded upon the magnet 3 between the member 22 and the base 50 of the pole piece 6 is a locking member 21 controlled by a lever 20 by which the magnet

3 is fixed in any position in which it is placed by the rotation of member 22.

Within the cup of magnet pole piece 6 there is located a magnetic shield 11 affixed to the base of the magnetic pole piece 6 by means of screws 31. The shield 11 surrounds the permanent magnet 3 to a point near its tip but sufficiently removed from the diaphragm 8 that the diaphragm will not strike the shield when vibrating at its maximum amplitude. The shield 11 is separated from the permanent magnet 3 by a small gap 32 to allow the free adjustment of magnet 3 toward and away from the diaphragm 8. The gap 32 may or may not be filled with insulating material.

Upon the central cylinder of shield 11 is wound the coil 10 which is held in form by the base of shield 11 upon one end and upon the other by a fibre or brass member 23. The terminals of coil 10 are soldered to the threaded brass tubes 15 within fibre blocks 16 mounted upon the base of pole piece 6. In the fibre blocks 16, the magnetic pole piece 6, and the casing 12 are aligned holes 17, 27, and 18 through which the connections to the coil 10 are made. The terminals of the leads to the coil 10 are held in position by means of screws 14 within the threaded brass tubes 15 within the fibre blocks 16.

It will be seen that there is only one gap in the magnetic circuit of this receiver as compared to two gaps or breaks in the magnetic circuit of most other receivers. The magnetic lines of force from the permanent magnet 3 pass through the diaphragm and across the gap at the center. As the attraction of any magnet for its armature is in direct ratio to the intensity of the field or to the number of lines of force that pass through it and as the number of lines of force from a magnet to its armature vary inversely as to square of the distance intervening it will be clear that the magnetic pull for a diaphragm of this type of receiver will be four times that of a receiver having two gaps in its magnetic circuit.

The lines of force set up in the current flowing in a coil 10 and acting on a soft iron cylinder or sleeve 11 surrounding the pole 3 also follow the magnetic circuit of the permanent magnet when the current is flowing in one direction in the coil thus adding to the strength of the permanent magnet and as the current changes amplitude or reverses direction, its magnetic lines of force,

being of opposite polarity will now attract nearly all of the lines of force from the center pole shielding the diaphragm and decreasing the attraction for the diaphragm to almost zero. The shield or cylinder 11 acts alternately as an added magnet pulling the diaphragm and as a shield for the diaphragm from the magnetism of the center pole. Because of this action the receiver 10 will be approximately four times more sensitive for any given ohmage winding than others of the two pole type.

In Figure 3 the outside pole piece 24 acts as a retainer for the receiver and an ear piece 15 25 is directly secured thereto. The shield may be eliminated here by using soft iron for the center pole piece 3 which is also adjustably mounted as indicated by the threads in part 24. A slot 26 permits the relative 20 25 adjustment with respect to the diaphragm 8 as and when desired.

While I have illustrated only two of various possible modifications it will, of course, be understood that others may be made without departing from the invention.

What I claim is:—

1. In a receiver of the character described, in combination, two pole pieces, one inside of the other, the outer pole piece being provided with a knife edge and a diaphragm supported from said knife edge.

2. In a receiver of the character described, in combination, two concentrically disposed pole pieces, the outer pole having a knife-edged periphery and a diaphragm supported therefrom and held in place by the magnetism of the center pole piece.

3. In a receiver of the character described, in combination, two concentrically disposed pole pieces, the outer pole piece having a knife-edged periphery and a diaphragm supported therefrom and held in place by the magnetism of the center pole piece and means whereby the center pole piece may be 45 adjusted towards and from the diaphragm.

4. In a receiver of the character described, in combination, two concentrically disposed pole pieces, a one piece metal diaphragm gradually tapering towards its periphery supported from the outer pole piece, said

center pole piece being adjustably mounted in the outer pole piece and a lock nut for holding said pole piece in adjusted position.

5. In a receiver of the character described, in combination, two concentrically disposed pole pieces, a coil there-between and magnetic means for shielding said coil on two or more sides to produce a differential effect in the magnetic field.

6. In a receiver of the character described, an outer pole piece, a central pole piece of soft iron and a magnetic shield surrounding said central pole piece and a coil mounted on said shield.

7. In a receiver of the character described, in combination, an outer pole piece, a central pole piece of soft iron and a shield surrounding said central pole piece, a coil mounted on said shield, a diaphragm, means for adjusting the central pole piece towards and from the diaphragm and a receiver case for said parts the ear piece of which tapers outwardly towards its aperture.

8. In a receiver of the character described, a cup-shaped outer pole piece, a centrally mounted pole piece coacting therewith and means associated therewith for supporting a coil and adapted to perform the functions of the aforesaid shield and center pole piece combined.

9. In a receiver of the character described, in combination, an ear piece tapering outwardly towards its aperture in the center on its under side, a one-piece metal diaphragm thinner near its outer edge, a knife-edge supporting the same, two magnetized pole pieces, one inside the other, the outer pole piece supporting said diaphragm, a magnetic shield on one side of the coil, a coil and means for mounting it on the magnetic shield, terminal connections for said coil, means for mounting the magnetic shield on the outer pole piece, means for adjusting and locking the outer pole piece in relation to the diaphragm and means for mounting the complete assembly in a receiver case.

Signed at Brooklyn, N. Y., this 1st day of Sept., 1923.

DAVID RONALD WALLACE.
